CONNECTER

William D. Kyle, Milwaukee, and Clarence J. Lemont, South Milwaukee, Wis., assignors to Line Material Company, South Milwaukee, Wis., a corporation of Delaware

Application December 11, 1933, Serial No. 701,764

26 Claims. (Cl. 173—263)

This invention relates to connectors.

It is an object of this invention to provide for electrical conductors, a connector which may be manipulated with one hand when connecting two or more conductors.

In comparing a connector embodying this invention with those of the prior art, it will be observed that the parts are so arranged to co-operate with each other and with the electrical conductors to be connected, that the operator may, with one hand, place the connector upon an electrical conductor and with the same hand operate the clamping elements, his other hand being free for other uses; whereas, the prior art connectors comprise elements which necessitate the use of both hands of the operator in applying the connectors.

A connector embodying this invention generally comprises but three elements related to each other in such manner, that they are always secured together regardless of whether or not they are in clamping relation to each other. It will be noted in the subsequent description that this device when applied to an electrical conductor is virtually supported by the conductor and engaged thereabout in such manner as to utilize the conductor as an element supporting the connector and serving as one of the means of preventing rotation of the connector when clamping the same. Obviously, this will permit the operator to use one of his hands for other purposes.

It is another object of this invention to provide a connector which, when supported by an electrical conductor, will have its parts so related at the beginning of the clamping operations, as to prevent the connector from being accidentally removed from the supporting conductor when the several parts are being manipulated to clamping engagement.

A further object of this invention is to provide a connector which may be manufactured by die-casting operation, and when so completed, will comprise but three elements requiring assembly.

A still further object of this invention is to provide a connector of the type noted which will maintain proper alignment of the several elements thereof, irrespective of the fact whether they may be assembled or disassembled in clamping relation.

Another object is to provide a connector of the type noted in which the clamping pressure is disposed at all times in a plane substantially parallel to the axis of the clamping nut, thereby placing the threads in direct line of pressure.

Another object is to provide a connector com-

prising simple elements necessitating a minimum number of operations in the manufacture and assembly of the several parts. This object may be accomplished by using standard material, such as, tubing, rods, and sheet metal.

In the drawings:

Figure 1 is a side elevation in vertical section illustrating the device as applied to a conductor.

Figure 2 is a side elevation in vertical section taken at right angles to the view in Figure 1.

Figure 3 is a side elevation in vertical section similar to Figure 2 showing a modified form of this invention.

Figure 4 is a side elevation in vertical section of a further modified form embodying this invention.

Figure 5 is a vertical section similar to Figures 2 and 3 showing a further modified form embodying this invention.

Figure 6 is a vertical view in section taken on the line 6—6 of Figure 7, showing a preferred modified form.

Figure 7 is a view in vertical section taken on the line 7—7 of Figure 6.

Figure 8 is a top plan view of the device shown in Figures 6 and 7.

Figure 9 is a view in perspective of a portion of the connector.

Fig. 10 is a view in side elevation of a modified form of the device shown in Fig. 6.

Throughout the several views, like parts are identified by the same reference characters.

The connector, shown in Figures 1 and 2, comprises a wire engaging member or bifurcated sleeve 1, a retainer 2, and a clamping nut 3. The wire engaging member 1 comprises a tubular element threaded upon its exterior periphery, provided with a shoulder 4 upon its interior periphery, and a transverse slot 5 upon opposite sides of the wire engaging member. The retainer 2 of the connector comprises a disc or plunger portion 6 substantially the diameter of the larger bore 7 of the wire engaging member 1, a second disc or closure portion 8 substantially the diameter of the smaller bore 9 of the wire engaging member 1, and a retainer disc 10 secured to the second disc portion 8, in any suitable manner, such as, rivet 11. The retainer disc 10 is of a diameter larger than the diameter of the wire engaging member 1 upon its outer periphery. Threadably mounted on the wire engaging member 1 is a clamping nut 3 which, as shown in Figure 1, forces the conductors 15 toward the bottom of the slots 5 in the wire engaging member 1.

55

It will be noted that the discs 2 and 8 of the retainer are connected at one side by means of the rod 14, which, in Figures 1 and 2, is segmental in cross-section. From this it will be seen that the disc 6 is held in contact with the adjacent electrical conductor 15 by reason of the fact that the retainer disc 10 is in engagement with the slotted end of the wire engaging member 1. In this manner the retainer portion 2 is drawn 10 into the wire engaging member 1, making a neat appearing connector and positioning the retainer portion 2 so that it will not be subject to injury.

If it is desired to remove the connector from the electrical conductors, it is necessary only to 15 rotate the clamping nut 3 in a direction forcing it toward the retainer disc 10. A continued rotation thereof will remove the clamping nut from engagement with the wire engaging member 1 and position it in supported relation upon the 20 retainer disc 10 and about the second disc or closure portion 8. When the several parts are in the relation noted, the wire engaging member 1 may be then lifted vertically to withdraw the 25 conductors 15 from the slots 5, until the lower margin of the wire engaging member 1 is disposed above the conductors and the disc portion 6 of the retainer is engaged with the shoulders 4. In this position the connector may be then moved sidewise to withdraw the conductors from 30 between the disc portions 6 and 8 of the retainer and from beneath the wire engaging member 1. Obviously, when the connector is applied to an 35 electrical conductor, the clamping nut 3 should be disengaged from the wire engaging member 1 and supported by the retainer portion 2 in spaced relation to the wire engaging element, to receive an electrical conductor between the disc portions 6 and 8 of the retainer and beneath the wire 40 engaging member 1. If the retainer portion 2 is positioned so that the electrical conductor is disposed angularly relative to the slots 5 in the wire 45 engaging member 1, the conductor may be engaged or brought into contact with the rod 14 of the retainer to hold the retainer in given relation thereto, and to permit the wire engaging member 1 to be rotated so that slots 5 will be 50 in registry with and directly above the conductor. When the parts are disposed as indicated, the disc portion 6 of the retainer may be positioned 55 upon the conductor and the wire engaging member 1 allowed to move downwardly with the conductor disposed in the slots 5 and until it is positioned upon the clamping nut 3. The clamping nut 3 may then be rotated into threaded engagement with the wire engaging member 1, further rotation thereof drawing the wire engaging member 1 into clamping relation with the conductor, as illustrated.

In assembling the device shown in Figures 1 60 and 2, the retainer portion 2 will be inserted into the larger bore 7 of the wire engaging member 1, in order to arrange the elements as shown and to receive the retainer disc 10 so that it may be riveted to the retainer portion as shown at 11. 65 The clamping nut 3 may then be positioned upon the wire engaging member 1 by passing it over the wire engaging end of the member 1.

Figures 1 and 2 illustrate a connector in which the wire engaging member 1 may be manufactured from standard tubular or rod material. The 70 retainer portion 2 may be manufactured from standard rod material. The retainer disc may be made of standard sheet metal material.

In manufacturing the wire engaging member 75 1 from standard tubular material, it obviously

will be necessary to upset one end to provide the shoulder 4, then to thread the outer periphery of the tube, and then to slot it transversely of its axis. In manufacturing the retainer portion 2, it would be necessary to turn the tube so that a portion will have the diameter of the disc portion 6 and a portion will have the diameter of the disc portion 8. In turning the retainer 2, a rivet will be left at the central portion of the disc portion 8 to be received in the aperture 16 in the retainer disc 10. It is, of course, apparent that the retainer disc 10 may be stamped out of standard sheet metal stock.

It is believed that all of the elements of the device described, lend themselves admirably to 15 die-casting operations, if it is so desired to manufacture the connector.

In Figure 3, the embodiment of this invention 20 comprises a wire engaging member 1 like that shown in Figures 1 and 2. The retainer, however, is constructed somewhat differently from that illustrated in Figures 1 and 2, the elements, however, being arranged to function in substantially the same manner as that previously described.

The retainer shown in Figure 3 comprises a 25 cupped plunger 20 having an eccentrically disposed aperture 21 receiving one end of the rod 22. This plunger 20 is substantially the same 30 diameter as the larger bore 7 of the wire engaging member 1. The retainer includes also a cupped closure 23 provided with a retainer flange 24 larger in diameter than the wire engaging member 1 and is provided with an eccentrically disposed aperture 25 receiving the rod 22. 35

Preferably the rod 22 is shouldered at each end as shown, for engagement with the adjacent cupped plunger 20 and cupped closure 23, and is riveted at each end to hold these respective parts securely upon the rod 22. As shown, the 40 rod 22 is disposed eccentrically relative to the wire engaging member 1 so that it will be positioned at one side of the slots 5 in the wire 45 engaging member 1, when the connector is assembled upon an electrical conductor.

The plunger 20 and the closure 23 may be formed out of standard sheet metal stock in a manner well known to those skilled in the art.

The retainer may be assembled in much the same manner in which the retainer 2 is assembled, as shown in Figures 1 and 2. The rod 22 may be first secured to the plunger 20, after 50 which the rod may be passed through the wire engaging member 1 with the plunger 20 disposed in the larger bore 7. The closure 23 may 55 be then secured to the rod, as illustrated. In use, the connector illustrated in Figure 3 will be manipulated in the same manner as that described in reference to Figures 1 and 2.

In Figure 4 the wire engaging member 28 comprises a bifurcated element similar to that illustrated in Figures 1, 2, and 3, but it is provided with a flange 29 at its conductor engaging end. It will be noted that this modified form of the wire engaging member is closed at its wire 65 engaging end, the closed end being provided with an aperture 30 disposed eccentrically relative to the wire engaging member 28 and receiving a wire 31 loosely positioned therein for movement longitudinally of its axis. The wire 31 is held 70 against retraction from the aperture by the beaded end 32. The wire terminates at one end in a loop 33 having a diameter greater than the diameter of the wire engaging member 28. This 75 looped end serves to retain the clamping nut 34.

3 in position to be engaged with the wire engaging member 28.

As shown, in Figure 4, the looped end 33 of the wire 31 may be continued into a smaller loop 34 which will serve to position the clamping nut 33 substantially for registry with the wire engaging member 28. The wire 31 is preferably reversely bowed intermediate its ends to provide an arm or plunger portion 35.

When a conductor is to be engaged by the connector shown in Figure 4, it will be passed between the wire engaging member 28 and the clamping nut 3 to register with the slots 5, in which position the arm 35 will rest upon the conductor. The wire engaging member 28 will then settle upon the clamping nut 3, thus entirely enclosing the conductor so that it will not accidentally be withdrawn from the slots 5. The nut 3 may then be threaded upon the wire engaging member 28 to draw the conductor into clamped relation to the bottom of the slots 5.

The modified form just described will be assembled by threading the nut 5 upon the wire engaging member 28 and then securing the wire 25 31 in position, as previously described.

Figure 5 illustrates a connector in which the wire engaging element 40 is similar to that shown in Figures 1, 2, and 3, with the exception that the wire engaging end is provided with a retainer flange 41. This wire engaging element is threaded on its exterior periphery to receive a clamping nut 3. The retainer shown in Figure 5 comprises a single piece of wire bent substantially as shown to form a plunger portion comprising two loops 42 superimposed one above the other and each substantially the diameter of the larger bore 7 of the wire engaging member 40, and to form a retainer end loop 43 and a closure loop 44. The closure loop is substantially the diameter of the smaller bore 9 of the wire engaging member 40. The retainer loop 43 is of a diameter larger than the diameter of the wire engaging member 40.

The device shown in Figure 5 is operated in the same manner as the devices previously described. When the device is being applied to a conductor or conductors, the conductor will be passed between the wire engaging member 40 and the nut 3 supported by the retainer loop 43. The retainer will then be supported by the conductor upon engagement of the lower plunger loop 42 with the conductor. The wire engaging member 40 will then be moved downwardly to position the conductor within the slots 5 and until it contacts with the nut 3. Thus it will be seen that the conductor is confined so that it cannot escape from the slots 5. To clamp the conductor, the nut 3 will then be threaded upon the wire engaging member 40 until it forces the conductor into engagement with the bottom of the slots 5 in the wire engaging member 40.

The retainer, as shown in Figure 5, operates in a manner similar to the retainers previously described. The loops 42 hold the retainer into alignment with the wire engaging member 40 for longitudinal movement therein. The retainer may be formed prior to its assembly on the wire engaging member 40. When the retainer has been formed as illustrated, the loops 42 may be inserted through the slots 5 at the lower end of the wire engaging member 40, by disposing the loops in planes extending longitudinally of the slots and then, after insertion through the slots, turning the loops to the position illustrated relative to the wire engaging member 40. Obviously,

when the loops 42 are being turned into the position illustrated, it will be necessary for them to spring relatively to each other to allow them to be properly positioned. Once the loops 42 have been properly positioned relative to the wire engaging member 40, they will maintain the retainer properly aligned.

Attention is directed to the fact that in the modified forms shown in Figures 4 and 5, the wire engaging members are each provided with a flange 29 and 41 respectively. These flanges serve to prevent removal of the clamping nuts from their respective wire engaging members after the arrangements have been assembled. Obviously, in assembling these modified forms, the nuts must be placed in position before the final assembling operations are completed. If desired, the modified forms, shown in Figures 1, 2, and 3, may be provided with flanges upon the wire engaging members 1 similar to the flanges 29 and 41, shown in Figures 4 and 5. In such cases the clamping nuts 3 will first be placed upon their respective wire engaging members 1 before the retaining portions 2 and retaining discs 10 are secured together as shown.

Figures 6, 7, 8, and 9, illustrate a preferred form of the invention disclosed herein. In this form the nut retainer maintains its relationship to the wire engaging member 50 so that there is no relative rotation between them, although they are freely slidable relatively axially to each other. This is similar in effect to that form shown in Figure 4 wherein the nut retainer always remains in alignment relative to the wire engaging member to receive electrical conductors. In this form, the space 70 in the nut retainer is always aligned for registry with the slots 55 in the wire engaging member 50.

In Figures 6, 7, and 8, the wire engaging member 50 is provided with the hexagonal end 51, a threaded sleeve having diametrically opposite slots 55 adapted to receive electrical conductors, and a beveled end 17 for guiding the clamping nut 53 for engagement with the threads on the wire engaging member 50.

The wire engaging member 50 is provided with a longitudinally extending aperture 57 with one of its walls coinciding with one of the walls of each of the slots 55, and the other of its walls being offset from the other of the walls of the slots 55. This longitudinally extending opening is rectangular in horizontal cross section, as will be noted in Figure 8, and receives the plunger 56 of the retainer for movement reciprocally thereof. The aperture 57 is provided on one side with a channel 54 extending from one end of the member 50 to a point adjacent the other end of the member, to provide a shoulder 54A. Integral with the plunger portion 56 is a lug 56A extending into the slot 54 and engageable with the shoulder 54A, thereby limiting the movement of the plunger in one direction.

The nut retainer shown in Figures 6, 7, 8, and 9, comprises the plunger 56, arm 61, and block 58, having arms 59 disposed on one side of the nut 53 and arms 60 disposed on the other side of the nut 53. The several elements of the retainer are connected as a unit and the arms 59, together with the block portion 58, serve as a jaw 71, cooperating with the jaw portion or bottom 72 of the slots 55. The jaws 71 and 72 are preferably each V-shaped as indicated at 71' and 72' in Figure 10. Thus, when electrical conductors are placed between the jaws, pressure exerted by the jaws upon the conductors will be substantially 75

directly disposed in a plane intersecting the axes of the conductors and parallel to the axis of the clamping nut 53. This will prevent the conductors from slipping sidewise relative to each other and to the jaws, and will dispose the clamping forces directly in line with the pitch of the threads. In other words, any tendency of the bifurcated ends of the clamping member to warp, or become distorted, will be substantially eliminated, if not entirely so. As a matter of fact, when the conductors are disposed as they are in this connector, the block portion 58 will be disposed between the bifurcated ends and serve as an additional strengthening element preventing distortion of the bifurcated ends of the wire engaging member.

The nut retainer shown separately in Figure 9 is illustrated as it appears after the die-casting operation. When completed, as shown, the lug 56A is disposed in a plane projecting upwardly from the plunger portion 56 so that the plunger portion may be inserted through the bifurcated end of the wire engaging member 50 into the aperture 51. After the plunger 56 has been inserted, it may be passed through the aperture 51 so that the lug 56A may be bent, as shown in Figure 6. When thus bent to extend into the slot 54, it serves as the retaining element for the retainer preventing withdrawal thereof from the wire engaging member 50. The arms 60 extend vertically from the block portion 58, as shown in Figure 9, after the completion of the die-casting operations. When the plunger has been secured in position, as previously noted, the nut 53 may then be positioned adjacent the arms 59 and the arms 60 bent to position them below the nut 53, as illustrated in Figure 7.

The modified forms, as illustrated in Figures 6, 7, 8, and 9, operate in much the same manner as our previously described forms. When it is desired to secure conductors together, they will be passed into the space 70 in the retainer and the retainer will be supported therefrom by the plunger 56. Then the wire engaging member 50 will be dropped vertically to enclose the conductors within the slots 55 and for engagement with the nut 53. Obviously, this connector may be operated with one hand when it is placed in position, as just noted, and then the nut 53 may be operated by the hand that positioned the connector, as noted.

The rectangular shape of the aperture 51 and the plunger 56 insures that the retainer and the member 50 will remain in the alignment illustrated in the drawings. A further element of strength to be noted resides in the fact that the arm 61 extends the full depth of the block 58 to serve as means for adding strength or support to the bifurcated end of the member 50 when the nut 53 is in clamping engagement therewith.

In each of the views, the wire engaging members are provided at their lower or bifurcated ends with a beveled edge 17 which serves to align the wire engaging members with their respective nuts 3 when the connector is being initially assembled on a conductor. This feature is of considerable importance, because it assists the operator in the use of one hand when assembling the connector.

The foregoing description discloses a connector comprising elements which may be manufactured and assembled at a minimum cost and which, when assembled, may be manipulated with one hand when placing the connector in engagement with a conductor and when clamping the con-

nector into engagement therewith. The disclosure herein illustrates a connector in which the conductors are positioned for clamping engagement so that they are retained in position for clamping by reason of the structural arrangement of the connector.

We have illustrated several modifications of the invention disclosed herein, but it will be understood that there are numerous other modifications which may be adopted, according to the requirements of the user. Therefore, the claims in this case should be interpreted in the light of the generic idea of this disclosure.

We claim:

1. A connector for electrical conductors, said connector comprising a pair of U-shaped members, one movable within the other and disposed at right angles thereto, said members being relatively extensible, whereby the inner U-shaped member may receive conductors, stop means limiting the relative extension of said members, and clamping means engageable with the outer member for clamping said conductors therein.

2. In a connector, the combination with two bifurcated members, one disposed within the other at right angles relative thereto, of means for confining said members in slidable relationship and for clamping conductors therein.

3. In a connector, the combination with a bifurcated sleeve having its bifurcated end threaded, of a nut threaded on said sleeve, a retainer reciprocally mounted in said sleeve for movement exteriorly adjacent said bifurcated sleeve, and means on said sleeve for limiting said movement in one direction, whereby to support said nut in spaced relation to said bifurcated end, said nut being mounted on said retainer for support thereby when removed from said sleeve.

4. In a connector, a bifurcated sleeve having its bifurcated end threaded exteriorly and provided with a shoulder interiorly, of a nut on said sleeve, a retainer reciprocally mounted relative to said sleeve and comprising a plunger in said sleeve engageable with said shoulder, and a retainer disc exteriorly of said sleeve, said plunger and disc being on opposite sides of said shoulder and said disc being larger in diameter than said sleeve.

5. In a connector, a bifurcated sleeve having its bifurcated end threaded exteriorly and provided with a shoulder interiorly, of a nut on said sleeve, a retainer reciprocally mounted relative to said sleeve and comprising a plunger in said sleeve engageable with said shoulder, and a retainer disc exteriorly of said sleeve engageable with said nut to retain it on said retainer, said plunger and disc being on opposite sides of said shoulder and connected by a link disposed eccentrically relative to the axis of said sleeve.

6. In a connector, a bifurcated sleeve having its bifurcated end threaded exteriorly and provided with a shoulder interiorly, of a nut on said sleeve, a retainer reciprocally mounted relative to said sleeve and comprising a plunger in said sleeve engageable with said shoulder, and a retainer disc exteriorly of said sleeve, said plunger and disc being on opposite sides of said shoulder and connected by a link disposed eccentrically relative to the axis of said sleeve, said disc being larger in diameter than said sleeve.

7. The combination with a bifurcated sleeve having its exterior periphery threaded, of a plunger reciprocal in said sleeve, a retainer element exteriorly of said sleeve having a diameter larger than the diameter thereof, said retainer

element being connected with said plunger, a clamping nut threadably engaged with said sleeve, and means on said sleeve between said plunger and retainer element for preventing said plunger from being withdrawn from the sleeve in the direction of said retainer.

8. In a connector, the combination with a bifurcated sleeve having a shoulder adjacent the bifurcated end thereof, a plunger reciprocal in said sleeve, a retainer exteriorly of said sleeve secured to said plunger, said plunger being limited in its reciprocal movement in one direction by said shoulder and in the other direction by said retainer, and a clamping nut threadably engaged with said sleeve, said retainer being adapted to support said nut in spaced relation to the bifurcated end of said sleeve.

9. In a connector, the combination with a bifurcated sleeve, a plunger reciprocal in said sleeve, a retainer exteriorly of said sleeve secured to said plunger in spaced relation thereto, means on said sleeve between said plunger and retainer for limiting the movement of said plunger in one direction, said retainer limiting the movement of said plunger in the other direction, and a nut threadably engaged with said sleeve.

10. In a connector, a bifurcated member adapted to be supported upon a conductor, means supported by the bifurcated member for securing the conductor thereto, and a second bifurcated member received by the first mentioned member in enclosed relation for engagement with said means, whereby the conductor will be confined within said bifurcated members during the clamping operations.

11. In a connector, the combination with a bifurcated sleeve having its bifurcated end threaded, of a nut threaded on said sleeve, a retainer reciprocally mounted in said sleeve for movement exteriorly adjacent said bifurcated sleeve, and means on said sleeve for limiting said movement in one direction, whereby to support said nut in spaced relation to said bifurcated end, said bifurcated end being beveled to align said nut.

45 12. In a connector, a bifurcated sleeve having its bifurcated end threaded exteriorly and provided with a bevel upon the end thereof, a nut on said sleeve, a retainer reciprocally mounted relative to said sleeve and comprising a plunger in said sleeve, and a retainer disc exteriorly of said sleeve, whereby said retainer may be positioned upon an electrical conductor and the sleeve moved to conductor retaining position for engagement with said nut, and means defining the limits of the reciprocal movement of said retainer.

13. In a connector, a bifurcated sleeve having its bifurcated end threaded exteriorly, a nut on said sleeve, a retainer reciprocally mounted relative to said sleeve and comprising a plunger in said sleeve, and a retainer disc exteriorly of said sleeve, whereby said retainer may be positioned upon an electrical conductor and the sleeve moved to conductor retaining position for engagement with said nut, and means defining the limits of the reciprocal movement of said retainer.

14. A connector comprising a clamping member having a threaded bifurcated end and an aperture axially thereof provided with at least one flat side, a retainer having a plunger portion complementary to said aperture, and a retainer jaw portion spaced from the plunger portion to provide a conductor receiving area, said area registering with the space in the bifurcated end and the retainer jaw portion being

receivable in said space, means defining the limits of plunger movement, and a nut rotatably supported by the jaw portion.

15. A connector comprising a clamping member having a threaded bifurcated end and an aperture axially thereof, one side of the aperture being grooved to provide a shoulder therein adjacent the bifurcated end, a plunger slidable in said aperture having a lug projecting into said groove, a retainer jaw receivable in the bifurcated end and connected with the plunger in spaced relation thereto, a nut rotatable on said retainer jaw, and means supporting the nut on said jaw.

16. A connector comprising a clamping member having a threaded bifurcated end, a plunger extending across the space in said end and slidable therein, a nut retainer spaced from the plunger and receivable in said space, means connecting said plunger and retainer, stop means on said plunger slidably engaging the member and limited in sliding movement by said member to a position adjacent the bifurcated end and within said space, and a nut rotatably supported by the retainer, said retainer being spaced from said member and supported directly in line with said space when said stop means is operative.

17. In a wire connector, the combination with a bolt element having an open ended slot extending upwardly therein for the reception of wires and a nut threadable upon the bolt to close the slot, of a protruding member extending from the nut receiving end of the bolt and upon which the nut is carried when disengaged from the bolt, and means carried upon the protruding member for retaining the nut against removal therefrom.

18. In a wire connector, the combination with a bolt element having an open ended slot extending upwardly therein for the reception of wires and a nut threadable upon the bolt to close the slot, of a protruding member extending from the nut reception end of the bolt upon which the nut when disengaged from the bolt is supported against complete removal from the connector.

19. In a connector, the combination with a wire engaging element having a bifurcated end provided with a thread, of a clamping nut engaging the thread, and means including a portion reciprocally mounted on said element and a portion projecting from said bifurcated end for supporting said nut from said end when disengaged from said thread, said nut being rotatively supported by said means when said nut is disengaged from said bifurcated element.

20. A connector comprising a clamping member having a threaded bifurcated end, a plunger extending across the space in said end, a nut retainer spaced from the plunger, means connecting said plunger and retainer, stop means connected to said plunger and cooperating with said clamping member to limit outward sliding movement of said plunger, and a nut rotatively supported by the retainer.

21. In a wire connector, the combination with a bolt having an open ended slot for the reception of wires and a nut threadable upon the bolt, of a protruding member extending from the nut receiving end of the bolt and upon which the nut is carried when disengaged from the bolt, and means carried upon the protruding member for retaining the nut against removal therefrom.

22. In a wire connector, the combination with a bolt having an open ended slot for the reception of wires and a nut threadable upon the bolt, of a protruding member extending from the nut

reception end of the bolt and upon which the nut when disengaged from the bolt is supported against complete removal from the connector.

23. In a wire connector, a threaded bolt having an open slot in the threaded portion of the bolt for mounting said bolt upon a wire, a nut threadable upon said bolt, wire clamping means carried by the nut, a nut support slidable in the slot, retaining means for holding said nut support slidably relative to said slot, and means connecting said nut support and said wire clamping means whereby said nut and wire clamping means may be removed from said bolt and held adjacent to open portion of said slot while said bolt is being mounted on a wire.

24. In a wire connector, a threaded bolt having a slot in the threaded portion of the bolt open at one end for mounting said bolt upon a wire, a nut threadable upon said bolt, wire clamping means carried by said nut, and means defining the limit of movement of said nut with reference to the open portion of said slot, whereby when said nut is moved to said limit of movement the open por-

tion of said slot will be operative for mounting said bolt upon a wire.

25. In a wire connector, a threaded bolt having a slot in the threaded portion of said bolt open at one end for the reception of a wire, clamping means including a nut threadable upon the bolt for closing the open end of said slot, and means projecting from said bolt adjacent the open end of said slot for slidably and rotatably supporting said clamping means for movement to a position spaced from and adjacent the open end of said slot.

26. In a bifurcated bolt connector having spaced legs and intervening wire slot, the legs being grooved longitudinally on their inner sides, and a nut threadable upon the bolt legs over the wire slot, means for operatively anchoring the nut to the bolt to permit the removal of the nut for admitting wires into the wire slot, the said means including elements slidably anchored in the said grooves of the legs of the bolt.
